LIGHTER FOR OIL BURNER STOVES

Carroll M. Breed, Ypsilanti, Mich., assignor to
United Stove Company, Ypsilanti, Mich., a
corporation of Michigan

Application July 26, 1940, Serial No. 347,741

12 Claims. (Cl. 158—90)

This invention relates generally to oil burning stoves having burners of the wick type and refers more particularly to improved means for igniting the wick.

Considerable difficulty and inconvenience have been encountered in the past in igniting the wick in an oil burner of the type commonly employed on stoves due to the fact that the combustion drum or chimney ordinarily renders the wick inaccessible. In the past it has been necessary to lift or tilt the drum or chimney in order to render the wick accessible for ignition and this is not only inconvenient but involves handling of the soiled drum which is objectionable.

It is, therefore, one of the principal objects of this invention to overcome the above objections by providing means rendering it possible to ignite the wick of an oil burning unit without handling or otherwise disturbing the chimney or combustion drum.

Another object of this invention resides in the provision of a wick having a section movable relative to the remaining portions of the wick through the chimney or combustion drum to a position substantially above the upper end of the latter where it may be conveniently ignited. After the movable section of the wick has been ignited, the latter is returned to its original position in operative relation to the wick and thereby serves to ignite the wick.

Still another object of the present invention resides in moving a section of the wick to its projected position where it may be conveniently ignited and returning the section of the wick to its original position with respect to the remainder of the wick for igniting the latter by remote control means located for convenient manipulation by the operator.

Another feature of this invention consists in the provision of remote control means positioned for convenient manipulation by the operator at the front of the stove and operatively connected to the movable section of the wick by means of a spring wire actuator possessing sufficient flexibility to permit bending the same within its elastic limits to various irregular shapes.

A further advantageous feature of this invention resides in the provision of a readily detachable connection between the movable section of the wick and the spring wire actuator. As a result, the movable section of the wick may be readily replaced when desired without the necessity of replacing the entire wick.

A still further object of this invention resides in the novel arrangement of the several remote control igniting means on a stove embodying a plurality of oil burning units. This feature, as well as the foregoing objects, will be made more apparent as the description proceeds, especially when considered in connection with the accompanying drawings, wherein:

Figure 1 is a semi-diagrammatic view, partly in section, illustrating my improved wick igniting means in association with an oil burning unit;

Figure 2 is a fragmentary elevational view of a part of the oil burning unit shown in Figure 1 and illustrating the lighting tip in operative relation to the wick;

Figure 3 is a sectional view taken substantially on the plane indicated by the line 3—3 of Figure 1;

Figure 4 is a plan view of a stove having a plurality of oil burning units and illustrating the arrangement of the remote controls for the igniter tips;

Figure 5 is a fragmentary sectional view illustrating one manner of attaching the lighting tip to the actuating wire;

Figure 6 is an elevational view illustrating still another means for attaching the lighting tip to the actuating wire.

Referring now to the drawings, it will be noted that there is illustrated in Figure 1 an oil burning unit 10 of the wick type having a wick tube 11 substantially U-shaped in cross section and having an annular wick 12 suitably supported in the wick tube. In accordance with conventional practice, the lower portion of the wick tube is adapted to contain a supply of fuel and the latter is conveyed to the top of the wick by capillary attraction. In the present instance, the lower portion of the wick tube communicates with a fuel reservoir 13 through the medium of a feed line in the form of a conduit 14 having a valve 15 therein for controlling the flow of the fuel from the reservoir 13 to the wick tube 11. The valve 15 is supported for convenient manipulation by the operator on the control panel 16 at the front side of the stove and the burner 10 is suitably secured to a part 17 of the stove in rear of the control panel 16.

The oil burner 10 is further provided with a pair of inner and outer perforated tubes 18 and 19 supported in concentric relation on the upper ends of the inner and outer flanges 20 and 21 respectively of the U-shaped wick tube. Both of these tubes are apertured to insure supplying the volume of air to the space above the wick tube required for efficient combustion and the outer perforated tube 19 is preferably surrounded by an air baffle tube 22. The air baffle tube 22 is suitably supported on the tube 19 in concentric relation to the latter and provides an annular space around the tube 19 for the flow of air. In accordance with conventional practice, a chimney or combustion drum 23 is supported with the side walls thereof concentric with the air baffle tube 22 and is constructed to facilitate the up-draft of air in proximity to the wick which is necessary in order to obtain efficient combustion. Wick type oil burner units of the general construction briefly described above have been used

extensively for a long period of time and although they operate satisfactorily for the purpose intended, nevertheless, they present the problem of igniting the wick without the necessity of lifting or tilting the combustion drum and associated parts to render the upper end of the wick accessible. As pointed out above, the present invention contemplates a relatively simple and inexpensive attachment to the burner rendering it possible to conveniently ignite the wick without disturbing or handling the combustion drum or associated parts of the burner. In detail, attention is directed to Figure 2 of the drawings wherein it will be noted that a portion 24 of the wick 12 is moved from the remainder of the wick and this portion will be referred to hereinafter as the lighting tip. In the present instance, the portion 24 or lighting tip has a length equal to the width of the annular wick so that the lower end of the lighting tip is saturated with the fuel contained in the lower portion of the wick tube.

The lighting tip is movable from the position thereof shown in Figure 2 wherein it forms a continuation of the wick to the full line position thereof shown in Figure 1 where it is elevated a substantial distance above the top of the combustion drum so that it may be conveniently ignited. The lighting tip 24 is moved between the concentrically arranged perforated tubes 18 and 19 by means of a spring wire actuator 25 having one end removably secured to the tip by either of the two methods shown in Figures 5 or 6. In Figure 5, the free end of the actuator is merely formed to provide a loop 26 and the tip is secured to the loop by means of a cotter pin type fastening element 27. In Figure 6, the tip is riveted to a lug 28 having a threaded sleeve 29 engageable with a correspondingly threaded portion 30 on the free end of the flexible wire actuator. In either case, the tip is readily removable and can be replaced when desired.

The spring wire actuator extends downwardly through a suitable opening formed in the base of the wick tube opposite the tip 24 and is extended through a casing in the form of a tube 31 having the upper end brazed or otherwise suitably secured to the wick tube. The casing 31 is bent to the shape required for convenient installation in the stove and serves to guide the flexible wire actuator throughout its movement relative to the casing.

As shown in Figure 1, the flexible wire actuator extends out of the free end of the casing 31 and is secured to a control rod 32 mounted for reciprocation on the stove. The control rod extends through a suitable opening formed in the control panel 16 of the stove and is provided with a handle 33 readily accessible from a position at the front side of the stove to reciprocate the rod. It will also be observed from Figure 1 that the rod is provided with a downwardly extending return bent portion 34 intermediate the ends and the end of the return bend is fashioned to form a loop 35. The loop 35 is adapted to receive a stud 36 having a head engaging one side of the loop and having a threaded shank portion extending through the loop to the opposite side of the latter for receiving a clamping nut 37. Upon reference to Figure 3, it will be noted that the shank is provided with an opening extending transversely therethrough and so located that it occupies a position between the clamping nut and adjacent side of the loop. This opening is adapted to receive the end of the flexible wire actuator extending from the free end of the tube 31 and

the actuator is clamped in place by tightening the nut 37. If desired, a pair of washers may be positioned on the shank of the stud at opposite sides of the flexible wire actuator to effect the clamping action. This arrangement provides a relatively simple, inexpensive attachment which lends itself to rapid assembly and disassembly.

It may be pointed out at this time that the delivery end of the tube 31 or, in other words, the end thereof adjacent the lighting tip 24 extends vertically and inasmuch as the length of spring wire is normally straight, it follows that the lighting tip is moved vertically or substantially vertically regardless of the bends in the casing 31. It may be pointed out at this time that the movement of the lighting tip 24 to its raised and lowermost positions is positively limited by means of a pair of stops 38 and 39 in the form of lugs welded or otherwise suitably secured to the rod 32 at points spaced from each other longitudinally thereof. The lug 39 is adapted to engage the inner side of the control panel 16 on the stove to limit the extent of upward movement of the lighting tip and the stop 38 is adapted to abut a part 40 of the stove structure to limit the downward movement of the lighting tip.

When the several parts of the igniting attachment are in the dotted line positions thereof shown in Figure 1, the lighting tip 24 assumes a position within the wick tube to form, in effect, a continuation of the wick. Assuming that the parts are in this latter position and that it is desired to ignite the burner, the operator merely exerts a pull on the rod 32 in an outward direction until the stop 39 on the rod engages the inner side of the control panel 16. As the rod 32 is moved outwardly by the operator, the spring wire actuator 25 is advanced relative to the casing 31 from the dotted line position shown in Figure 1 to the full line position shown in the same figure. As a result, the lighting tip is elevated to a position substantially above the combustion drum 23 and may be conveniently ignited. After the lighting tip is ignited, the operator merely pushes the rod 32 inwardly until the stop 38 abuts the frame member 40. This inward movement of the rod returns the lighting tip to its original position in the wick tube and communicates the flame to the remainder of the wick.

The above construction not only affords a relatively simple, inexpensive and convenient arrangement for igniting the wick but, in addition, is of a nature to occupy the minimum space so that a number of units may be installed in a stove without the necessity of increasing the size of the latter. In this connection, attention is directed to Figure 4 wherein it will be noted that two pairs of burners 42 and 43 are diagrammatically illustrated in the positions they normally assume in a stove. In the present instance, the rear pair of oil burning units are respectively equipped with igniting attachments 44 and 45 supported adjacent each other in the space provided between the burner units of each pair. The front pair of burner units 43, on the other hand, are respectively provided with igniting attachments 46 and 47 suitably supported at opposite sides of the stove. The particular construction of the igniting attachments shown in Figure 4 and the manner in which the latter are operatively connected to their respective burners are the same as previously described in connection with Figure 1. Accordingly, the illustration in Figure 4 is merely diagrammatic and is for the sole purpose of illustrating the convenient man-

ner in which the lighting attachments may be arranged on the stove.

What I claim as my invention is:

1. In a wick type oil burner, an annular wick having a section movable relative to the remainder thereof and forming a lighting tip, and means for elevating said section for ignition purposes.

2. In a wick type oil burner, an annular wick having a portion thereof movable relative to the remaining portion and forming a lighting tip, and manually operable control means accessible for manipulation at a point remote from the burner and connected to the movable portion of the wick for elevating said movable portion to a position substantially above the wick.

3. In a wick type oil burner, a wick having a portion forming a continuation thereof and movable relative to the remaining portion, means for supplying fuel to the wick and movable portion, air directing means supported above the wick and substantially concealing the latter, and means for elevating the movable portion of the wick to a position above the air directing means for igniting purposes and for returning said movable portion to said wick for igniting the latter.

4. In a wick type oil burner, a wick having a movable portion normally forming a continuation of the wick and providing a lighting tip, means for supplying fuel to the wick and movable portion, a flexible linear member having one end connected to the lighting tip, a reciprocable control member connected to the other end of the flexible linear member for operating the latter to raise the lighting tip relative to the remainder of the wick and return the lighting tip to its normal position with respect to the wick, and means for guiding the flexible linear member throughout movement thereof by said control member.

5. In a wick type oil burner, a wick having a movable portion normally forming a continuation of the wick and providing a lighting tip, a length of spring wire having one end connected to the lighting tip, a reciprocable control member connected to the other end of the spring wire, and a tubular guide for the spring wire cooperating with the spring wire upon movement of the control member in one direction to raise the lighting tip to a position where it may be conveniently ignited and upon movement of the control member in the opposite direction to return the lighting tip to its normal position with respect to the wick wherein the latter is ignited by said tip.

6. In a wick type oil burner, an annular wick tube substantially U-shaped in cross section and adapted to contain fuel, an annular wick supported in the tube with the lower end immersed in the fuel and having a section movable relative to the remaining portion of the wick, air directing means extending above the wick tube and substantially concealing the upper end of the wick, and means operatively connected to the movable section for elevating the latter above the air directing means and for returning said movable section to its normal position with respect to the wick.

7. In a wick type oil burner, a wick tube substantially U-shaped in cross section and adapted to contain a quantity of fuel, an annular wick located in the wick tube with the lower end immersed in the fuel and having a section movable relative to the remaining portion of the wick, a tube connected to the bottom of the wick tube

opposite the movable section thereof, a flexible linear member extending through the tube and having one end secured to the movable section, and a reciprocable control member connected to the other end of the flexible linear member for actuating the latter to raise the movable section of the wick relative to the remainder thereof and to return said movable section to its normal position with respect to the wick.

8. In a wick type oil burner, a wick having a section thereof movable relative to the remaining portion of the wick to a position substantially above the wick, means for moving said section including a flexible linear member having one end removably secured to the movable section, and a control member operatively connected to the other end of the linear member for actuating the latter.

9. In a wick type oil burner, a wick tube substantially U-shaped in cross section and adapted to contain a supply of fuel, an annular wick supported within the wick tube and having a section movable relative to the remaining portion thereof, an air directing drum surrounding the wick tube and extending above the latter, a tubular guide member having one end secured to the bottom of the wick tube opposite the movable section of the wick, a length of spring wire slidably mounted in the tubular guide and having one end secured to the movable section of the wick, and a control member connected to the opposite end of the length of spring wire for actuating the wick to a position above the upper end of the air directing drum and for returning the movable section to its normal position with respect to the wick.

10. In a wick type oil burner, an annular wick having a section movable relative to the remaining portion thereof to a position substantially above the wick, a pair of air directing tubes concentrically supported above the wick in alignment with the latter, and means operatively connected to the movable section of the wick for moving the latter upwardly between said tubes to a position above the tubes and for returning the movable section of the wick to its normal position relative to said wick.

11. An oil burner comprising a circular channel and having a wick therein, shells mounted on said channel, said wick being formed of two pieces, one piece extending about a major portion of the circumference of the channel, the other portion extending about the remaining minor portion of the channel, and means attached to said minor wick portion for removing it from said channel and shells to a position where it may be ignited, and means for returning and guiding said minor wick portion to its original position between the ends of said major wick portion.

12. In a wick oil burner, a wick, a burner part surrounding the wick and projecting above the wick, a lighting tip for the wick normally supported in flame transmitting relation to the wick for movement in an upward direction through the burner part to a position where it may be conveniently ignited and for return movement to its normal position in flame transmitting relation to the wick, a member connected to the lighting tip for selectively raising and lowering the same to the above mentioned positions, and a control for operating said member.
